UNITED STATES PATENT OFFICE.

BERT F. LUICK, OF POMONA, CALIFORNIA, ASSIGNOR TO ARTHUR W. RISHER, OF SPADRA, CALIFORNIA.

WIRE-REEL.

1,191,904.

Specification of Letters Patent. Patented July 18, 1916.

Application filed July 6, 1914, Serial No. 849,098. Renewed October 11, 1915. Serial No. 55,357.

To all whom it may concern:

Be it known that I, BERT F. LUICK, a citizen of the United States, residing at Pomona, in the county of Los Angeles, State of California, have invented new and useful Improvements in Wire-Reels, of which the following is a specification.

This invention relates to a reel for winding and unwinding coils of wire.

10 It is the object of this invention to provide a reel which is adjustable to suit coils of various sizes and diameters, and to provide a simple and effective means for making such adjustment.

15 A further object is to provide adjusting means by which the coil can be made to fit tight on the reel as portions are unwound therefrom, which can be operated while the reel is in rotation.

20 A further object is to provide an expanding reel which is so constructed that the parts will not bind and thereby prevent its effective operation.

The invention is illustrated in the accompanying drawings, in which:

Figure 1 is a plan view of the reel, with parts broken away. Fig. 2 is a view in side elevation with parts removed. Fig. 3 is an enlarged detail section on the line 3—3 of Fig. 1, partly in elevation. Fig. 4 is a detail section of one of the sliding blocks as seen on the line 4—4 of Fig. 2, in the direction indicated by the arrows.

More specifically, 6 indicates a frame 35 which is formed of parallel side members 7 and 8 fitted with hand-holds 9 by which it may be readily carried; the members 7 and 8 being connected together by transverse beams 10 and 11, and a central beam 12.

40 Mounted on the beam 12 intermediate its ends is a bearing plate 13 and extending upwardly from this plate 13 is a standard 14, the lower end of which is reduced and passes through the plate 13 and the beam 12 and is engaged by a nut 15 on the underside of the beam 12 by which it is held in place.

Revitably mounted on the standard 14 and supported on the bearing plate 13 is a hub 16 formed with an outwardly extending flange 17 on its upper edge to which is secured a circular reel disk 18; the disk 18 being engaged with the flange 17 by means of bolts 19 which also engage a flange 20

formed on the lower end of a tubular externally threaded standard 21 encompassing the standard 14. The disk 18 is formed with a series of radially extending slots 22 and has a downwardly extending flange 23 on its periphery; certain of the slots 22 forming guide-ways for slidable blocks 24 and alternating slots being provided to permit the placing of a binding wire around a coil of wire supported on the disk 18. The flange 23 is provided to form a blunt edge 65 on the disk 18 and also to shield a series of rollers 25 revolvably mounted in yokes 26 carried by the rails 7 and 8. The rollers 25, preferably four in number, are spaced equidistant around the disk 18 adjacent to and 70 parallel with its outer edge and are normally positioned slightly out of contact with the lower face of the disk 18 so that the latter will contact therewith when there is sufficient load on the disk to depress its outer 75 edge into contact with the rollers; the disk 18 being formed of sheet metal and having a slight resiliency, but of sufficient rigidity that considerable pressure is necessary in order to compress the plate 18 sufficiently 80 to contact the rollers 25. This construction is provided for the purpose of preventing binding of the disk 18 as will be later described.

The blocks 24 extend through the slots 22 85 and are fitted with rollers 27 and 28 on each side thereof which are adapted to bear on the upper and lower sides respectively of the disk 18. The outer ends of the blocks 24 are formed with yokes 29 in which are 90 pivoted wire engaging arms 30, the upper ends of which are bent outwardly to coöperate with the disk 18 to prevent lateral spreading of a coil of wire carried on the arms 30 when the reel is disposed in a vertical position.

Pivotedly connected to the arms 30 a short distance above their pivotal connection with the yokes 29 are links 31 which extend inwardly and upwardly and are connected at 100 their inner ends to lugs 32 formed on a sleeve 33 slidably mounted on the threaded standard 21. Formed on the upper end of the sleeve 33 is an annular flange 34 which is slidably engaged by an internally threaded 105 sleeve 35 mounted on the standard 21 and provided with hand-holes 36 on its opposite sides by means of which it may be rotated

to cause it to advance up or down on the standard 21 to spread or retract the arms 30. The connection between the sleeve 33 and the sleeve 35 is detachable and is formed by providing the sleeves 35 with an open slot 37 on one side thereof through which the flanges 34 on the sleeve 33 may be passed so that the lower edge of the flange 34 will seat on an inwardly extending flange 38 formed on the sleeve 35 immediately below the slot 37.

As a means for rotating the reel the standard 21 is formed with a squared upper end portion 39 to receive a crank 40 which may be applied and removed as desired. By the use of the crank 40 the standard 21 and the disk 18 may be rotated independent of the reel adjusting sleeves 33 and 35 and without effecting the operation or adjustment of the latter. The upper end of the standard 14 projects beyond the upper end of the standard 21 and is threaded to receive a nut 41 which serves to hold the standard 21 in place.

25 In the operation of the invention, when it is desired to place a coil of wire on the disk 18 the crank 40 is removed and the arms 30 are retracted as indicated in dotted lines in Fig. 2, by rotating the sleeve 35 in such direction that it will move upwardly on the threaded standard 21, thereby causing the sleeve 33 to move therewith and exert an inward pull on the links 31, thus rocking the arms 30 rearwardly on their 35 pivotal connections with the links and the yokes 29. Continued upward movement of the sleeve 35 will operate to cause the blocks 24 to be retracted in their guide slots 22 so as to dispose the rearwardly inclined arms 40 30 adjacent the standard 21 when it is desired to place a coil of wire of small diameter on the reel. After the coil of wire has been positioned on the plate 18 around the outer faces of the arms 30 the sleeve 35 is 45 rotated so as to advance it downwardly on the standard 21 and thereby move the sleeve 33 therewith so as to cause the links 31 to rock the arms 30 outwardly toward their normal vertical position, which position is 50 limited by the lower ends of the arms 30 coming in contact with the forward ends of the blocks 24. Continued downward movement of the sleeves 35 and 33 would then cause the arms 30 and blocks 24 to advance 55 simultaneously to position the outer faces of the arms 30 in close contact with the inner periphery of the wire coil.

As it is desirable to have the wire coil tightly engaged by the arms 30 the threaded sleeve 33 is screwed downwardly so as to exert a considerable outward pressure on the arms 30 through the links 31. This action tends to bind the blocks 24 on the plate 18 but this binding action is effectively overcome by reason of the engagement of

the rollers 27 and 28 on the opposite sides of the plate 18. Likewise, the thrust of the links 31 acts to depress the outer portion of the plate 18 into contact with the rollers 25; a slight movement of the plate being permitted before contact with the roller 25 is effected by reason of the spaced relation of the rollers to the underside of the disk 18. This construction is important in that it obviates binding of the disk 18; it being found in practice that where the rollers contact the plate and the sleeve 35 screwed down to a point on the standard 21 to obtain the desired pressure of the arms 30 against the inner periphery of the wire coil that the disk 18 would be so tightly clamped against its bearing as to inhibit its rotation. When the wire coil is thus engaged on the disk 18 by the arms 30 the rails 7 and 8 are lashed to a post in a vertical position and the wire 85 is unwound from its coil. When it is desired to wind the wire on the reel the crank 40 is attached to the threaded standard 39 as shown in Fig. 2. It is manifest, however, that the reel may be operated both in winding or unwinding the wire coil when positioned horizontally, as shown in the drawings.

What I claim is:

1. A wire reel, comprising the combination of a frame, a stationary standard thereon, an externally threaded tubular standard revolvably mounted on said stationary standard, a disk rigidly affixed to the threaded standard formed with a series of radially extending slots, blocks slidably mounted in certain of said slots, arms pivoted on said blocks, links connecting with said arms above their pivotal connection with the blocks, a sleeve slidably mounted on the threaded standard to which the inner ends of said links are pivotally connected, a flange on said sleeve, and a threaded sleeve on said standard formed with an inwardly extending flange detachably engaging the flange on the loose sleeve.

2. In a wire reel, a frame, a revoluble disk on said frame, a plurality of rollers normally positioned out of contact with the underside of said disk and adapted to engage therewith on deflection of the disk under pressure thereon, whereby binding of the disk is prevented.

3. A wire reel, comprising a frame, a rigid standard thereon, a hub revolvably mounted on said standard, a disk supported on said hub, a threaded tubular standard encompassing the stationary standard, said threaded standard, disk and hub rigidly connected together, a plurality of blocks slidably mounted in radial slots in said disk, rollers on said blocks engaging the upper and lower surfaces of the disk, pivoted arms carried by said blocks, a loose sleeve on the threaded standard, links connecting said

sleeve to the pivoted arms, a threaded sleeve on said standard connected to the loose sleeve in revoluble relation thereto, whereby rotation of the threaded sleeve will operate to move the loose sleeve to rock the arms and shift the blocks.

In witness that I claim the foregoing I

have hereunto subscribed my name this 23rd day of June, 1914.

BERT F. LUICK.
